(57) **CLAIM**

The ornamental design for a mobile terminal display screen with a graphical user interface, as shown and described.

DESCRIPTION

FIG. 1 is a front elevation view of a first image of a mobile terminal display screen with a graphical user interface according to a first embodiment;

FIG. 2 is a front elevation view of a second image thereof;

FIG. 3 is a front elevation view of a third image thereof;

FIG. 4 is a front elevation view of a fourth image thereof;

FIG. 5 is a front elevation view of a first image of a mobile terminal display screen with a graphical user interface according to a second embodiment;

FIG. 6 is a front elevation view of a second image thereof;

FIG. 7 is a front elevation view of a third image thereof;

FIG. 8 is a front elevation view of a fourth image thereof;

FIG. 9 is a front elevation view of a first image of a mobile terminal display screen with a graphical user interface according to a third embodiment;

FIG. 10 is a front elevation view of a second image thereof;

FIG. 11 is a front elevation view of a third image thereof;

FIG. 12 is a front elevation view of a fourth image thereof;

FIG. 13 is a front elevation view of a first image of a mobile terminal display screen with a graphical user interface according to a fourth embodiment;

FIG. 14 is a front elevation view of a second image thereof;

FIG. 15 is a front elevation view of a third image thereof; and,

FIG. 16 is a front elevation view of a fourth image thereof.

The appearance of the animated images sequentially transitions between the images shown in FIGS. 1-4, 5-8, 9-12, and 13-16. The process or period in which one image transitions to another forms no part of the claimed design. The dashed
